[57] CLAIM

The ornamental design for a wood stove, as shown and described.

DESCRIPTION

FIG. 1 is a perspective view of a wood stove showing our new design;

FIG. 2 is a front elevational view thereof;

FIG. 3 is a right side elevational view thereof;

FIG. 4 is a rear elevational view thereof; and

FIG. 5 is a top plan view thereof.

The stovepipe has been shown fragmentarily in FIGS. 1, 3, 4 and 5 for convenience of illustration.

FIG. 1

FIG. 2

FIG. 3
